UNITED STATES PATENT OFFICE.

JAMES CRAN, OF CHICOOEE FALLS, MASSACHUSETTS, ASSIGNOR TO THE
A. G. SPALDING & BROTHERS, OF NEW YORK, N. Y.

DESIGN FOR A GOLF-CLUB.

SPECIFICATION forming part of Design No. 27,190, dated June 8, 1897.

Application filed April 21, 1897. Serial No. 633,193. Term of patent 7 years.

To all whom it may concern:

Be it known that I, JAMES CRAN, a citizen of Great Britain, residing at Chicopee Falls, in the county of Hampden and State of Massachusetts, have invented and produced a new and original Design for Golf-Clubs; and I do hereby declare the following to be a full, clear, and exact description of the invention, such as will enable others skilled in the art to which it appertains to make and use the same.

In the accompanying drawings, Figure 1 shows the working side of a golf-club head embodying the novel design. Fig. 2 is a top view of the same head. Fig. 3 is a section on the line 3 3, Fig. 1.

As shown in the drawings, the head consists of a body A, having at one end a handle-socket B, continuous with the main portion of the body and extending obliquely upward therefrom. In general outline, as shown in Fig. 1, that end of the body opposite the socket is rounded, and from this rounded end it is gradually narrowed in passing toward the socket. The general face C of that side of the head shown in Fig. 1 lies in a plane somewhat oblique to the plane of the body and socket, and from the central portion of this face projects a low broad boss D, having a face approximately parallel to the plane of the sur-

rounding and lower face C and contrasting 30 with that face in roughness of surface. In outline this boss is similar to the face from which it projects, but the ratio of its length to its width is less. As shown in Figs. 2 and 3, that side of the body which is opposite the 35 face C is ovoid, and its surface merges in that of the socket at one end, the nearly-cylindrical face E at the other end, the plane upper surface F, and the plane downwardly-inclined lower surface G. All the surfaces just 40 mentioned are continuous, except as they are broken by certain screw-heads H H H, and are continuous with each other, and the last three of them meet the face C in its marginal lines. At its narrow end the face C is continuous, with a forwardly-curved surface C' 45 intersecting the surface of the socket which lies partly in front of the plane of the surface C.

What I claim is—

The design for a golf-club, as herein shown and described.

In testimony whereof I affix my signature in presence of two witnesses.

JAMES CRAN.
